DISINTEGRATOR OF LABORATORY TEST
SIZE FOR WET DISINTEGRATION OF
CELLULOSIC PULP SAMPLESRobert M. Levy and Ward D. Harrison, Brevard,
N. C., assignors to Ecusta Paper Corporation, a
corporation of Delaware

Application May 3, 1944, Serial No. 533,982

2 Claims. (Cl. 92—22)

1

This invention relates to method and means for determining the disperse viscosity of cellulose, and more particularly to a specially designed wet disintegrator that enables the operator to use moist pulp samples. Dry samples may be used but are not required as they are in the conventional determination heretofore used. The procedure and machine are well adapted to mass-production control in a pulp and paper mill and may be utilized by unskilled labor and at a rapid rate with high degree of reproducibility of test results.

Heretofore, the commonly used viscosity determinations involve the major problem of rapidly obtaining accurate weight of the wet pulp sample. This usually requires some means for rapidly passing a blast of warm air through the wet pulp sample. In some cases this drying treatment is preceded by washing of the pulp with acetone, which involves an expensive solvent recovery.

Rapid drying of the sample sometimes causes degradation of the pulp that results in a decrease in the viscosity. Also, in actual practice, the dried pulp sample cannot be disintegrated without changing the moisture content upon exposure to the atmosphere. Furthermore the dried pulp samples usually require variable amounts of solvent.

In accordance with the present invention, the foregoing difficulties that characterize the prior practices, are overcome. The wet disintegration system of this invention avoids any pretreatment of the pulp, and enables immediate, rapid use of the wet pulp without drying, and provides accurate, rapid determination of the viscosity.

The method comprises the procedure of wet disintegration of the pulp to give a low consistency pulp suspension, followed by measurement of the latter in a fixed volumetric quantity for dissolving in cupriethylenediamine solvent, and finally measurement of the viscosity of the resulting solution with suitable equipment such as a capillary viscometer. For determining the consistency of the pulp suspension being tested, an aliquot of the disintegrated pulp suspension is filtered and dried on a heated steam cylinder in a few minutes time and weighed. This operation can be carried out simultaneously with the viscosity determination above mentioned and thereby saving considerable amount of time.

Wet disintegration of the pulp is a fundamental feature of this new viscosity determination and a machine especially adapted for that purpose has been developed. It comprises a closed cham-

2

ber for holding the pulp and relatively large volume of water, and inlet and drain connections; a rotary beater roll and a cooperating, resiliently mounted bed-plate between which the pulp is disintegrated. After the beater roll has been rotated for about 5 minutes the pulp is disintegrated and dispersed in the water to give a fluid, low consistency pulp suspension which may be measured in a pipette.

The details of construction of the disintegrator machine and method of operation thereof will be clearly understood by reference to the following description of the accompanying drawings in which:

15 Fig. 1 is a top plan view;
Fig. 2 is a side elevation;

Fig. 3 is a section taken on or about the lines 3—3 of Figs. 1 and 2;

Fig. 4 is an enlarged detail view of beater roll 20 and the bed-plate in cooperative relation to each other;

Fig. 5 is a top plan view of the bed-plate; and
Fig. 6 is a section on the line 6—6 of Fig. 4.

Referring now to the drawings in detail, the 25 numeral 10 designates the main body plate or base member of the supporting frame of the machine, the same being mounted on legs or standards 11 having rubber or other suitable cushioning pads 12 on circular foot flanges 13 at the lower ends thereof.

Extending up from the main body plate or base member 10 is a pair of rigid, vertical frame plates 14 having base-footing flanges 15 that are bolted or otherwise fastened securely on the top side of said base member 10. These frame plates 14 are spaced a sufficient distance apart to receive and support between them a generally cylindrical, hollow, body member 16, which is held securely therebetween by tie-rods 17 having their end portions extended through aligned holes in said plates 14 and secured by jam nuts 18 that are tightened against the adjacent outer face portions of the plates.

The cylindrical hollow body member 16 provides the working chamber in which the respective samples of wet pulp material are received and therein disintegrated. This cylinder, as shown, has an opening at the top thereof, which is normally closed by a cover 19, that rests on the body member 16 as shown at 20, and is sealed in its closed position by a gasket or the like 21. The cover 19 is provided with a strap-like handle 22, the middle portion of which is raised in spaced relation to the cover itself, with end portions 23 projected beyond opposite sides of the cover.

These end portions 23 of the handle member are formed with open-ended slots (see Fig. 1) to receive bolts 24 that are hingedly mounted in bifurcated lugs 25 provided on the adjacent outer face portions of the frame plates 14 (see Fig. 2) whereby said bolts 24 can be swung into and out of the slotted end portions 23 of the handle member. The bolts 24 are provided with wing-nuts 26 that are tightened upon the underlying handle extensions 23 to hold the cover in its closed and sealed position on the body cylinder 16. By this same token the wing-nuts 26 are readily loosened and the bolts 24 swung out of place to permit opening of the closure 18, at will.

Located within the body cylinder 16 is a rotor 27 comprising a cylindrical body having its circumferential portion formed with longitudinal grooves 28 cut rectangularly and radially therein and affording sharp corners at opposite sides of the several ribs 29 produced by the said longitudinal grooving of the cylindrical body and thus constituting the body as a "beater roll" and the same will be generally so termed hereinafter. This rotor 27 (see Fig. 6 for details) is provided with stub-shafts or spindles 30, 31, at its ends, the same being placed with a drive or forced fit in axial bores provided for the purpose in the rotor body or otherwise fixedly secured to the body.

When the rotor 27 is placed in working position in the body cylinder 16, the shaft members 30, 31, are projected outside the same through aligned openings in its end walls and the adjoining frame plates 14. Sleeved on said shaft members are packing elements 32 of rubber or other material suitable for the purpose pressed tight against the adjacent outer face portion of the contiguous frame plate 14 surrounding the opening therein through which the shaft member extends. The pressure of each packing element 32 is exerted and controlled by a follower-plate 33, abutting the adjacent side of the same and being mounted slidably on screw-studs 34 projected from the adjacent frame plate. These studs 34 have thereon jam-nuts 35 that are screwed up against said follower plate 33 so as to compress the interposed packing element with such compacting deformity and flow thereof to seal effectively the opening in frame plate 14 to prevent leakage of the pulp water content of the working chamber in the body cylinder 16, yet not offering any undue frictional resistance on the shaft member to interfere with rotation of the beater roll under motor power to be presently described.

The shaft member 30 has a reduced end portion 36 (see Fig. 6) that is journalled in a bearing 37 at the upper end of a standard 38 (see Figs. 1 and 2). This standard 38 is of an inclined form, it having a base portion 39 bolted or otherwise secured firmly on top of the base-plate 10 of the machine adjacent one side thereof and extending upwardly and inwardly so that the journal-bearing portion 37 overhangs at the middle of the base-plate and thus affords ample clearance for the placing of a bed-plate in and removing it from working position in the machine, as will be later described more specifically.

The opposite shaft member 31 has a portion thereof reduced in diameter, as at 40, and journalled in a bearing 41 at the top of a standard 42 whose base portion 43 is secured medially on the base-plate 10. The reduced shaft portion 40 is extended some distance beyond the journal bearing 41 and is provided at its end with a cou-

pling element 44, which latter is arranged and adapted for a detachable but interlocking engagement with a complementary coupling element 45 on the end of an aligned driving shaft 46.

The driving shaft 46 may be, directly, the armature shaft of the electric motor 47 as shown more or less conventionally in the drawings, or, if desired, there may be a conventional speed reduction or speed change gearing (not shown) interposed between the driving shaft 46 and the armature shaft of the motor, in any approved manner. But, in any case, the entire machine will be embodied practically in a compact, self-contained structure. As shown, the motor 47 is mounted on a vertical frame plate 48 having an angular foot extension 49 which is bolted or otherwise secured rigidly on the base-plate 10 adjacent the end thereof.

At the bottom of the cylindrical hollow body 16 is a bed-plate or block 50 which is mounted with capability of an up-and-down movement in opposed, abutting, cooperative relation to the beater roll portion of the rotor 27, the top face of this element 50 being hollowed out arcuately crosswise thereof and corresponding substantially to the curvature of the roll 27.

The top face portion of the bed-plate or block 50 is grooved-and-ribbed longitudinally in a manner similar to the groove and rib formation of the circumferential portion of the beater roll 27, but on a diagonal thereto, so that, when said roll 27 is rotated in its peripherally-opposed relation to the bed-plate or block 50, a substantial shearing and disintegration and dispersement of the fibers occurs rapidly. This produces the desired fluid, highly dispersed pulp suspension which can be measured in a pipette as hereinbefore described as to the purposes of the present invention.

The bed-plate or block 50 works in a rectangularly-walled opening 51 which extends transversely of the cylindrical body 16 at the bottom thereof. This elongated opening 51 is closed at one end, as at 52 (see Fig. 6), but it is open throughout its length, at the bottom, and is also open at its opposite end (see Figs. 4 and 6). The opening 51 is located in a substantial, thickened enlargement 53 of the bottom portion of the cylindrical body 16 (see Fig. 4) and the bottom of the opening is covered by a sheet of rubber or other suitable waterproof resilient material 54 which is, in effect, a diaphragm, and the same is secured to the under side of the thickened body portion 53 by a rectangular frame 55 screwed, bolted or otherwise fastened in place. So, too, the adjacent overlying face portion of the body enlargement 53 is preferably recessed, as at 56, to lend ample capability to the diaphragm 54 for upward movement of the bed-plate or block 50 which is supported directly thereon (see Figs. 4 and 6).

Bearing constantly against the under side of the diaphragm 54 is a top-rounded, upstanding lug 57 which extends across the inner end portion of a lever-plate 58 that is hingedly mounted between the pair of frame plates 14 of the machine (see Figs. 1 and 3). The outer end portion 59 of this lever-plate 58 is tapered, and at the extreme end portion thereof is an upstanding lug 60 having a knife-edge at its top. This knife-edged lug 60 engages in a substantially counterpart notch in the bottom edge portion of a flat, plate-like, lever-bar 61 which is hingedly mounted at one end, as at 62, on a bracket extension 63 of the base-plate 10 of the machine. This lever-bar

61 extends for a considerable distance from its pivotal support and is provided at its free end with a weight 64 (see Figs. 1 and 2). The weight 64, as shown, is of cylindrical form and it is provided with an axial bore therethrough, so as to be fitted removably on an upstanding stud 65 provided on the adjacent end portion of the lever-bar 61.

In practice, the weight 64 is of a predetermined, definite size and weight to cause the lever-bar 61 to exercise sufficient downward pressure on the outer end portion of the lever-plate 58 and thereby tilt said plate to raise the inner end portion thereof so that its lug portion 57 presses against the diaphragm 54 and correspondingly lifts the supported bed-plate or block 50 and maintains the same in constant engagement with the cooperating beater roll 27 thereabove. In this connection, instead of a single weight being used, a number of weights of different sizes and relative weight may be provided and used to vary the effective pressure exerted on the bed-plate 50 in the operation of the machine.

In order to raise the lever-bar 61 and hold it in an inoperative position, as occasion may require from time to time, a rotary cam member 66 is located under said bar (see Figs. 1 and 2). As shown, this cam element 66 is fixed on the end of a shaft 67 which extends across the base-plate 10 of the machine and is journalled in eye-bolts or the like 68 mounted on the base-plate 10 near the opposite side margins thereof, and the shaft being held against longitudinal movement by collars 69 secured thereon and opposingly abutting said eye-bolts or bearing members 68. At the other end of the shaft 67 is a handle member 70, which, as shown, is provided by turning the end portion of the shaft downwardly at a right angle, thus making the handle an integral part of the shaft.

The cam element 66 is located normally below the lever-bar 61 to permit freedom of movement of the latter in its functional operation, but, when turned, the high side of said cam element engages and lifts the lever-bar; and, to hold the parts in their engaged relation, the high side of the cam element is flattened off as shown more clearly in Fig. 2.

The chamber in the cylindrical body 16 is filled, as hereinbefore stated, through the top opening which is normally closed and sealed by the cover 19. In order to drain said chamber after use, there is provided an inclined discharge spout or tube 71 which opens at its inner end into the chamber of the cylindrical body 16 adjacent the bed-plate or block 50 (see Fig. 3). Slidable longitudinally in this spout or tube 71, with a leak-tight fit, is a valve-pin or rod 72 which is releasably fastened in place by a set-screw 73 entered through a threaded opening provided for the purpose in the side of the spout or tube (see Figs. 1 and 2).

The inner end of the valve-pin or rod 72 is beveled off arcuately, as at 74 (see Fig. 3), in order to conform to the inner surface curvature of the adjacent bottom portion of the chamber in the cylindrical body 16; and, to prevent turning of the valve-pin or rod in the spout or tube 71, it is provided with a radial pin or lug 75 which enters an open-ended, longitudinal slot 76 formed in the end of the spout or tube. This slot-and-pin provision enables the ready insertion and removal of the valve-pin or rod 72, at will, and at the same time holds the positioned valve element against rotation.

For the purpose of flushing out the chamber of the cylindrical body 16, either before or after use, a water pipe 77 is tapped into the body enlargement 53 of the cylindrical body 16, which body portion is provided with a passageway and port 78 opening into the recessed portion 56 above the confining diaphragm 54. Thus, when the bed-plate or block 50 is withdrawn (as it so capable of being) the water supplied from the pipe 77 flows up through the empty space where the bed-plate or block 50 has been removed, and into the chamber above, from whence it is drained out through the discharge spout or tube 71, which latter is provided both for the purpose of this flushing drainage and the removal of the fiber disintegrated and dispersed wet pulp as aforesaid.

In use, the machine is placed over a drain pan or tray 79, which latter, as shown, is open at one end as at 80. In order that the pan or tray 79 is inclined downwardly from its closed end to its open end, when placed on a level, horizontal bench, table or other flat surface in use, a rubber strip 81 of a definite thickness (say, $\frac{1}{8}$ inch) is secured across the underside of the tray near its closed end (see Fig. 3) and, at a short distance therefrom, another strip 82 or less thickness (say $\frac{1}{16}$ inch) is secured; or, in other words, the pan or tray 79 is supported at intervals so as to give the desired pitch or slant thereto to facilitate drainage. The particular reason for supporting the pan or tray 79 by the said strips 81 and 82 is that, in addition to giving the proper slant to the pan or tray, the strips are placed in substantially the exact position where two of the legs 11 of the supporting frame of the machine are placed on the bottom of the pan or tray in use (see Fig. 3). In this way, the pan or tray has its necessary drainage slant and at the same time the machine is supported solidly on the pan or tray bottom and without undue vibration in its operation. A splash guard 84 is placed about the machine.

To facilitate the placing and removing the bed-plate or block 50 in and from the working position on the cylindrical body 16 of the machine, the hereinbefore described bearing standard 38 is inclined and supported at its base out of the way of the element 50. The outer end portion of said element 50 is formed and projected in any approved manner for its convenient engagement and manipulation for its placement and removal, and such end portion may be fastened in place in any approved or conventional manner, such as, for example, by a retainer 83 as indicated more or less conventionally in Figs. 2 and 6.

Various modifications and changes may be made in the machine and method described hereinabove without departing from the scope of this invention, as defined in the appended claims.

We claim:

1. A disintegrator of laboratory test size adapted for wet disintegration of cellulosic pulp samples for disperse viscosity determinations, comprising a cylindrical chamber for containing said wet pulp samples, a grooved rotor member disposed for rotation in said chamber in peripherally-opposed relation to an internal wall portion of said chamber, said chamber being formed with a recess at said wall portion and said recess having a lateral opening, a grooved block removably positioned in said recess in opposed relation to said rotor member, said grooved

block being transversely removable from said recess through said lateral opening without disturbing said rotor member, a resilient diaphragm closing the bottom of said recess and supporting said grooved block, and a weighting means bearing externally on said diaphragm for biasing said grooved block against said rotor member under a predetermined constant pressure.

2. A disintegrator of laboratory test size adapted for wet disintegration of cellulosic pulp samples for disperse viscosity determinations, comprising a cylindrical chamber for containing said wet pulp samples, an access opening in said chamber for introducing said wet pulp samples, a grooved rotor member disposed for rotation in said chamber in peripherally-opposed relation to an internal wall portion of said chamber, said chamber being formed with a recess at said wall portion and said recess having a lateral opening, a grooved block member removably positioned in said recess in opposed relation to said rotor member, said grooved block being transversely removable from said recess through said lateral opening without disturbing said rotor member, a resilient diaphragm closing the bottom of said recess and supporting said grooved block, a weighting means bearing externally on said diaphragm for biasing said grooved block against said rotor member under a predetermined

constant pressure, a drain conduit from said chamber for removing the disintegrated pulp samples, a valve element in said conduit presenting a face flush with the internal wall of said chamber in closed position, and a second conduit running to the recess in said chamber whereby said chamber may be flushed when said grooved block is removed.
